UNITED STATES PATENT OFFICE.

GEORGE W. MIX, OF BATAVIA, NEW YORK, ASSIGNOR TO F. E. MASON & SON, OF BATAVIA, NEW YORK, A COPARTNERSHIP.

EMBOSSING MACHINE.

1,410,212.

Specification of Letters Patent. Patented Mar. 21, 1922.

Application filed June 10, 1920. Serial No. 387,835.

To all whom it may concern:

Be it known that I, GEORGE W. Mix, a citizen of the United States, residing at Batavia, in the county of Genesee and State 5 of New York, have invented new and useful Improvements in Embossing Machines, of which the following is a specification.

This invention relates to an embossing machine which is more particularly designed 10 for making embossed labels or seals either with or without a variety of colors.

One of the objects of this invention is to provide improved means for carrying and guiding the strip of material from which the 15 labels or seals are made past the impressing mechanism.

Another object of this invention is to improve the means for inking the die when the labels or seals are to be embossed in colors.

20 This invention has the further object to so construct the machine that the same will operate with a minimum power, wear and noise and permit of producing labels or seals more expeditiously and economically.

25 In the accompanying drawings:

Figure 1 is a vertical longitudinal section of an embossing machine embodying my invention, showing the die raised from the counter. Figure 2 is a fragmentary view 30 of the same character, showing the die lowered and co-operating with the counter for producing an embossed label. Figure 3 is a similar view of the feeding-off device. Figure 4 is a side elevation of the machine viewed from the left. Figure 5 is a perspective view of the spreading lever for separating the main feed-off roller and the return roller. Figure 6 is a cross section taken on line 6—6, Fig. 1. Figure 7 is a fragmentary 35 longitudinal section, on an enlarged scale, of the inking mechanism taken on line 7—7, Fig. 6. Figure 8 is a vertical transverse section of the same taken on line 8—8, Fig. 1. Figure 9 is a fragmentary side elevation of the machine viewed from the right. Figure 45 10 is a rear end elevation of the machine. Figure 11 is a horizontal section of the machine taken on line 11—11, Fig. 1. Figure 12 is a fragmentary transverse section taken 50 on line 12—12, Fig. 11. Figure 13 is a fragmentary vertical longitudinal section, on an enlarged scale, taken on line 13—13, Fig. 11. Figure 14 is a fragmentary horizontal section, on an enlarged scale, taken on line 55 14—14, Fig. 10. Figure 15 is a fragmentary

transverse section taken on line 15—15, Fig. 4. Figure 16 is a fragmentary vertical transverse section taken on line 16—16, Fig. 1.

Similar characters of reference indicate 60 corresponding parts throughout the several views.

The main frame of the machine may be of any suitable construction to support the several working parts, but as shown in the 65 drawings, the same preferably comprises a horizontal longitudinal table or bed 20, legs 21 supporting said table at opposite ends thereof, and two standards 22 rising from said table adjacent to its opposite longitudinal edges.

Between the standards and above the table is arranged the counter 24 which is normally stationary and co-operates with a vertically 70 movable die 25 arranged above the counter 75 for producing impressions on the material from which the labels are made, the opposing surfaces of this die and counter being provided with complementary engravings of the designs of which embossed reproductions are to be made. The die and counter are preferably so constructed that in addition to producing an embossed impression on the strip, this embossed portion is 80 cut out of the body of the strip so as to 85 complete the label or seal. The counter is preferably fixed on a supporting plate 26 which latter rests on a carrying block 27 and is held against horizontal displacement thereon by means of dowels 28 arranged on the 90 underside of the supporting plate and engaging with sockets 29 in the carrying block, as best shown in Fig. 12. This block, together with the counter and associated parts 95 is capable of vertical adjustment for properly positioning its impression surface relatively to the die co-operating therewith. The means for this purpose shown in the drawings, have been found satisfactory in practice and comprise a guide base 30 secured to the top of the table and provided with a vertical guide opening 31 in which the counter block 27 slides vertically, a wedge 32 movable horizontally and transversely between the underside of the counter 100 block and the upper side of the table, an adjusting screw 33 engaging its inner threaded end with a threaded opening in the wedge and having its outer end journaled in a bracket 34 on the adjacent part of the table, 110

a collar 35 secured to said screw and engaging with the inner side of said bracket and a crank or handle 36 secured to said screw and engaging with the outer side of said bracket. Upon turning the adjusting screw by means of the crank the wedge will move either inwardly or outwardly and thus raise the counter and permit of lowering the same by pressure. This screw 10 is able to operate in this manner by reason of the fact that the same is journaled on the bracket 34, so as to be incapable of longitudinal movement therein.

The vertical movement of the die 25 may 15 be effected in various ways, but as shown in the drawings this is accomplished by mounting the same on the underside of a vertically movable cross head 37 which is provided on its underside with a recess 38 in which a stem 39 on the upper side of the die is secured by a set screw 40, as shown in Figs. 1 and 2. This cross head slides at its opposite vertical edges in gibbs or guideways 41 on the standards, and is reciprocated vertically by means of a driving crank shaft 42 journaled in bearings 43 at the upper ends of the standards and having its crank 45 connected by a link or pitman 46 with the upper side of the cross head. The crank shaft 30 may be driven in any approved manner, for instance, by a driving belt passing around a pulley 47 on one end of the crank shaft, this pulley being heavy enough to serve as a fly wheel.

35 The labels or seals 48 which are produced by this machine are simultaneously embossed and cut successively from a strip 49 of paper which is moved intermittently across the space between the counter and die and operated on by the same step by step. This strip is preferably supplied from a roll 50 arranged in rear of the die and counter and passes from this roll forward between the die and counter where the labels are embossed and cut therefrom and then leaves at the rear end of the machine where the labels are separated from the perforated waste or remnant of the strip. The means for moving the strip forwardly through the 45 machine include an endless feeding belt or band 51 of pliable material such as a woven fabric filled with rubber which band has its upper operative stretch arranged lengthwise above the table and supporting the label strip on its underside, while the same is engaged by the guiding and feeding mechanism in front and in rear of the die and counter and while passing between the same. At the front end of this table are arranged 50 the means for supporting the strip roll and the means for guiding the strip and band before the same reach the die and counter. These front supporting and guiding means are constructed as follows:

55 52, 53 represent the front and rear sections

of an adjustable shelf, the rear shelf section 53 being connected by brackets 54 to the front end of the table and the front section 52 being slideable lengthwise on the rear section and guided as well as held frictionally 70 in its adjusted position relatively thereto by a plurality of hook-shaped clips 55 secured to the longitudinal edges of the rear shelf section and overhanging the corresponding edges of the companion front section, as 75 best shown in Figs. 1, 4, 6 and 11. The strip roll is pivotally mounted on a bushing 56 which turns on a transverse spindle 57. The latter is secured at one end to a guide disk 58 and to the upper part of a bracket 80 59 which is mounted on the adjacent part of the front shelf section. The spindle, bushing and disk are tilted transversely, so that the arbor and spindle incline or slope downwardly from their outer ends to their inner 85 ends, whereby the strip roll when placed on the bushing will always tend to move by gravity toward the disk, so that when the same is turned as the strip is unwound therefrom, the roll will be free without liability of becoming detached from the bushing and without requiring any separate means for retaining the roll on the bushing. The tendency to frictionally resist the turning movement of the roll is minimized 90 by arranging a small washer 60 on the bushing between the inner end of the strip roll and the guide disk, whereby the greater part of the inner side of this roll, when evenly wound, is held away from the guide disk and the roll is caused to turn freely. In case the roll is wound unevenly or loosely the guide disk prevents the same from becoming so irregular as to interfere with the unwinding of the strip from the roll and its 100 proper presentation to the mechanism which subsequently operates on the strip.

At its front turn the supporting and feeding band passes around the front edge of the front shelf section and adjacent to the front side of the disk and counter the strip and band come together and pass in unison through a front guide which includes upper and lower guide rods 61, 62 arranged transversely over the table. The rods are 110 connected adjacent to opposite longitudinal edges of the strip and band by guide blocks 63 which are adjustable transversely on these rods to suit the width of the band and strip, this being preferably accomplished by 115 providing these blocks with holes through which the rods pass and set screws 64 which clamp the same on the rods after adjustment. The guide blocks may rest on the table and the same are held in place by means of two supporting arms 65 arranged lengthwise on opposite sides of the strip and band and connected at their rear ends with opposite ends of the upper guide rod 61 while their front ends are pivotally connected by 130

- screws 66 or otherwise with opposite longitudinal edges of the rear table section and thus permit the guide rods and blocks to be raised when necessary and permit of more conveniently adjusting the parts and passing the feeding band and label strip through this guide. By sliding the front shelf section forwardly or backwardly, the same may be adjusted to suit the length of the feeding and supporting band and enable any undue slack in its lower stretch to be taken up, and it also permits of arranging the roll in the best position relative to the front guide according to the width and character of the strip which is being operated upon.
- On the rear side of the die and counter are arranged the part of the means whereby the label strip supporting band are moved forwardly intermittently which means comprise a main feeding roller 67 arranged transversely in rear of the main frame and an upper gripping roller 68 which is arranged above the main feed roller, the strip and band passing forwardly in a superposed position between these rollers. The main feed roller is mounted on a transverse shaft 90 which is journaled in bearings on the side pieces 69 of a supplemental frame mounted on the rear end of the table and an intermittent rotary motion is imparted to this roller by mechanism which connects the same with the crank shaft 42. This mechanism in its preferred form, as shown in Figs. 6, 9, 10 and 11, comprises a ratchet wheel 70 connected with the main feed roller shaft 90, a ratchet arm 71 swinging on the latter and having a spring pressed pawl 72 engaging with said ratchet wheel, an elbow lever 73 pivoted on the main frame and having its lower arm connected with the ratchet lever by a horizontal connecting rod 74, and an upright eccentric rod 75 connected at its lower end with the upper arm of said elbow lever while its upper end is provided with a strap 76 surrounding an eccentric 77 on the main crank shaft 42. During each rotation of the latter which occurs for each cycle of operations of the machine, the ratchet lever makes a forward active and a backward idle stroke, whereby the main feed roller is turned forwardly one step while the die is raised from the counter, so that the strip and band are advanced and then this roller is permitted to stand still, so that the strip and band are at rest while the die and counter are pressed together and produce an impression on the strip and sever a finished label or seal from the body of the strip. For the purpose of enabling the distance which the strip is fed forward during each step to be varied to suit the length of the label or seal which is being produced, adjusting means are provided which consist of a bolt 78 arranged on the rear end of the lower rod 74 and adapted to engage one or another of a row of openings 79 in the ratchet arm, a bolt 80 arranged on the front end of the rod 74 and adjustable radially in a slot 180 in the lower arm of the elbow lever 73, and a bolt 81 arranged on the lower end of the upright rod 75 and adjustable radially in a slot 82 in the upper arm of said elbow lever.
- The upper gripping or pressing roller 68 is turned by frictional contact with the strip and is preferably made in two sections, as shown in Figs. 10 and 11, which engage the upper side of the strip adjacent to its opposite longitudinal edges, so as not to bear against the finished labels or seals which at this time are still arranged in the opening of the body of the strip and are liable to stick to the latter, but are subsequently separated therefrom. These gripping roller sections 68 are mounted on a transverse shaft 83 which is journaled at its ends in bearings 84. The latter are provided with depending guide pins 85 which slide in lugs 86 on the supplemental frame and are yieldingly held in a depressed position by springs 87 connecting these bearings with side bars 88 of the supplemental frame, so that the roller 68 presses the strip and band against the periphery of the main feed roller and enables the latter to advance the strip and band properly. In order to cause the strip and band to wrap around the main feed roller to a considerable extent and insure a positive feeding action of the same, a guide rod 89 is arranged transversely over the main feed roller adjacent to the front side thereof and adapted to be engaged on its underside by the strip. The gripping roller 68 and the guide rod 89 have their lowermost surfaces arranged below the uppermost surface of the main feed roller, whereby the strip and band are wrapped a considerable extent around the feed roller and thus insure reliable feeding of the strip and band. The guide rod 89 is loosely supported at its opposite ends in openings in the side pieces 69 and held against lengthwise movement therein by cotter pins 91 engaging with the outer sides of these side pieces. On its central part the guide rod 89 is provided with two guide fingers 92 which are adjustably secured thereto by screws 93 so that they may be engaged with opposite edges of the strip and band and confine the same in place relatively to the impression and feeding devices. These fingers preferably project forwardly from the rod 89 and rest loosely on the adjacent cross piece 94 of the supplemental frame, as shown in Figs. 1, 4 and 11. At its rear turn the supporting band passes downwardly around a guide rod or roller 95 which is carried at its ends on the rear parts of the side bars 88 and at this place means are provided for causing

the label strip and the band to be directed away from the band and the finished labels or seals to be separated from both the strip and band. The means for this purpose consists of a separator or stripper 96 having the form of a blade arranged transversely in rear of the guide rod 95 and supported at its ends on the side bars 88 and having a comparatively sharp scraping edge 97 which engages with or is arranged close to the descending portion of the band at the rear turn of the latter. If labels or seals which have been embossed and cut from the strip tend to stick to the band the same will be removed therefrom by the scraping edge of the separator blade, so that the labels or seals drop from the band at its rear turn, as shown in Fig. 13, while the cleared part of the band passes idly underneath the table and the perforated part of the strip from which the labels have been removed passes forwardly over the separator blade and disposes of the waste in any suitable manner. For the purpose of causing the delivery portion of the supporting band between the main feeding roller and the guide rod to be held taut and drawn effectively around this guide rod, so as to insure proper and prompt separation of the labels or seals from the strip, means are provided which produce a pulling effect on that part of the band adjacent to the guide rod 95 but leave the remaining part of the band comparatively slack. The means employed for this purpose comprise a tension roller 98 which is arranged transversely below the main feed roller and between which rollers the band is gripped and moved to the front turn of the same. The tension roller is turned by frictional engagement with the band which is pressed against the main feed roller for which purpose the tension roller is journaled at its ends in bearings 99 sliding on guide rods or bolts 100 depending from the side pieces 69 of the supplemental frame and are yieldingly held in their elevated position by springs 101 surrounding these guide rods and engaging their upper ends with the underside of the bearings 99 while their lower ends engage with heads on said rods, as shown in Figs. 2, 3, 4 and 10. Due to variation in the thickness of the label strip and other causes, the strip at times is liable to become unduly slack between the guide rod or roller 89 and the tension roller and when this occurs the attendant periodically depresses the tension roller and pulls the lower stretch of the band forwardly until its slack is taken out of that portion of the same between the tension roller and the guide roller 89 and permits the tension roller to again resume its pressure against the band and main feed roller. The preferred means for thus separating the main feed roller and tension roller consists of two rocking

cams 103, one of which is arranged between the upper side of each bearing 99 and the adjacent side piece 69, and a curved cross bar or handle 104 connecting said cams. Normally, these cams present narrow faces 70 to the opposing faces of the bearings 99 and side pieces 69, as shown by full lines in Fig. 3, but upon turning these cams so that their wide faces engage said side pieces and bearings, the gap between the same is 75 increased and the tension roller is separated from the main feed roller, as shown by dotted lines in the same figure, so that the attendant is free to move the band for eliminating slack therein between the tension 80 roller and rear guide roller 89.

When the labels or seals are designed to have a color in addition to that already present on the strip of which the labels or seals are made, an inking mechanism is provided whereby the face of the die is provided with a coat of ink, so that the impression produced by the same will be colored as well as embossed. The preferred means for accomplishing this purpose are constructed as follows:

In its general organization, the main elements of this inking mechanism are mounted on the cross head which carries the die, so that the inking mechanism rises and falls 95 with the die and the latter may be coated with ink without loss of time, thus increasing the output of the machine. The ink is delivered to the die from an ink distributing plate 105 which preferably has the form 100 of a disk and is arranged in front of the die and has its underside or face flush therewith. In front of the distributing plate is an ink fount 106 from which the ink is delivered through the passage or outlet formed 105 between the bottom of this fount and a supply roller 107 journaled transversely on the lower part of this fount. The ink is transferred from the supply roller 107 to the underside of the distributing plate by 110 a transfer roller 108 which moves back and forth between the supply roller and the disk, and the ink is deposited upon the face of the die by one or more delivery or depositing rollers 109 which are movable back 115 and forth between the distributing disk and the die. Various means may be provided for supporting the inking mechanism on the vertically-movable cross head and actuating the same in harmony with the impressing 120 operation, but as shown in the drawings, this is effected by the following means:

110 represents two horizontal rails or tracks arranged lengthwise underneath the crosshead on opposite sides of the die and 125 distributing disk. At their front ends each of these guide rails is supported by brackets 111 which are connected with the front side of the cross head. At their rear ends these rails are connected by a transverse bridge or 130

cross piece 112 which latter is in turn connected with the cross head by means which permit of adjusting the rail vertically relatively to the cross head and thus bring the ink delivery devices into the proper position to best ink the die according to the character of the same and the nature of the work which is to be produced. The adjusting mechanism for this purpose shown in the drawings consists of an L-shaped bolt 113 having a lower portion which is secured to the rear side of the cross head while its upper vertical part passes through an opening in the central part of the cross piece 112, and screw nuts 114, 115 applied to said bolt above and below said cross piece. By turning the nuts 114, 115 so that they move either up or down, the rear ends of the rails will be adjusted accordingly, and then may be held reliably in position by tightening the bolt of these nuts. Movable lengthwise in guideways formed on the inner sides of the rails are two slides or runners 116 which are connected by a cross bar forming a carriage. The ink transfer roller is journaled transversely on the front ends of the slides of the carriage and the two delivery rollers are journaled transversely on the rear ends of said slides in such position that when this carriage is reciprocated horizontally and lengthwise of the machine, the transfer roller will engage alternately with the ink supply roller and the distributing disk and the delivery rollers will engage alternately with the distributing disk and the face of the die. To guard against an excess amount of ink from being deposited on the die, the ends of the delivery roller engage with a pair of horizontal gage bars 118 which are secured lengthwise to the underside of a plate which is in turn secured to the underside of the cross head so that the undersides of the gage bars are flush with the face of the die and distributing disk. The front ends of these gage bars are beveled or rounded, as shown at 119 in Fig. 2, so as to permit the delivery rollers to pass freely from the disk to the gage bars without liability of interference or injuring any of the parts. The reciprocating movement of the carriage supporting the ink transferring and delivery rollers is effected by means which are driven from the cross head, which means include a bifurcated main rock lever 120 having the hub at its upper end mounted loosely on a horizontal rock shaft 121 arranged transversely in front of the cross head while its lower arms straddle the ink fount and the guide rail and are connected at their lower ends with opposite sides of the inking carriage by links 122 which are arranged lengthwise on opposite sides of the path of the strip and band. The rock shaft 121 is journaled transversely in bearings formed on the front ends of brackets 123 which are secured to the front sides of the standards. The hub of the rock lever 120 is forked and between its sections the upper end of an intermediate short rock lever 124 is secured while its lower end is adjustably connected with the main rock lever 120 at a point between the shaft 122 and the ink fount by means which preferably consist of an adjusting rod 125 pivotally connected at its rear end with the intermediate rock lever while its front end passes through an opening in the main rock lever and is provided with screw nuts 126, 127, engaging with the front and rear sides of the main rock lever. Projecting forwardly from the cross head is a bracket 128, the front end of which is connected with the intermediate rock lever 124 by a link 129. By means of this mechanism the inking carriage is moved inwardly under the cross head for inking the die while the cross head is being raised from the counter and strip, as shown in Fig. 1, and while the cross head is lowered for pressing the die upon the strip, band and counter and producing a label or seal, the inking carriage is withdrawn outwardly from between the cross head and counter, as shown in Fig. 2. By shifting the screw nuts 126, 127 on the rod 125, the position of the main rock lever relatively to the intermediate rock lever may be adjusted for bringing the delivery rollers of the inking carriage into the desired position relative to the die of the cross head. The ink fount is secured at its opposite ends to the front ends of the guide rails, and the discharge of ink through the outlet thereof is regulated by an inclined regulating plate 130 secured at its upper end to the upper part of the fount and bearing at its lower end against the ink supply roller, and a plurality of regulating screws 131 arranged in the front wall of the ink fount and bearing against the outer side of the regulating plate. By tightening or loosening the screws 131, the gap between the regulating plate and the ink supply roller may be varied to suit the rate of discharge of ink from the fount as required. The ink supply roller is turned intermittently by motion derived from the main rock lever 120, this being preferably accomplished by a ratchet wheel 132 secured to the shaft of the ink supply roller outside of the fount, a ratchet arm 133 turning concentrically with this ratchet wheel and having a pawl 134 engaging with this ratchet wheel, a shifting link 135 pivotally connected with the main rock lever 120 and having a longitudinal slot 136, and an adjusting bolt 137 adapted to be adjusted lengthwise in a longitudinal slot 138 in the ratchet arm 133 and movable along the slot 136 in said link. During the forward movement of the main rock lever 120, the link 135 slides idly on 139

the bolt 137 until the front end of its slot 138 engages, and thereafter the ratchet arm 133 and main rock lever move together to the end of the forward stroke of the latter, and 5 during the backward stroke of the main lever the link 135 slides idly on the bolt 137 until the rear end of its slot engages the bolt 137 and the ratchet arm is moved backwardly to the end of the stroke in this 10 direction with the main rock lever. By this means a comparatively short throw of the ratchet lever which operates the ink supply roller is obtained notwithstanding that the main lever 120 has a comparatively long 15 throw, thereby producing a slow feed of ink from the fount. By adjusting the bolt 137 up or down in the slot 138, the amount of ink which is fed may be adjusted as required. The ink distributing disk is so 20 mounted and operated that the same is rotated slowly and intermittently for the purpose of evenly distributing the ink and causing the die to be inked uniformly. The approved means shown in the drawings for this 25 purpose comprise an upright shaft 139 which carries the ink disk at its lower end and has its upper end journaled in a bearing formed in a cross bar 140 which is secured to the upper sides of the guide rails, a horizontal shaft 141 journaled transversely in bearings on said cross bar and operatively connected at its inner end with the upper end of the disk shaft by a pair of intermeshing bevel gear wheels 142, a ratchet 30 wheel 143 secured to the outer end of the shaft 141, a ratchet arm 144 mounted loosely on the shaft 141 and having a pawl 145 engaging with the ratchet wheel 143 and provided with a longitudinal slot 146, a ratchet 35 arm 147 secured to the rock shaft 121, and a link 148 provided at one end with a bolt 149 which is adapted to engage with one or another of a row of openings 150 in the rock arm 147 while its opposite end is provided with a bolt 151 adapted to be adjusted along a longitudinal slot 152 in the ratchet arm 147, these connections between this link and said arms permitting of adjusting the length of the steps of the intermittent 40 rotary movement of the ink distributing disk as may be required to get the best results.

In the operation of this machine, the strip and supporting band are fed forwardly and 45 a new part of the strip is presented to the impressing mechanism while the die is elevated from the counter and at the same time the inking of the die is being effected and when the die descends, the inking mechanism is withdrawn from beneath the same and the strip and band are at rest and the die produces an impression on the strip.

These operations are performed easily and quickly without an undue expenditure of 50 power and without producing any noise or

wearing any of the parts rapidly, thereby enabling labels and seals to be produced economically.

I claim as my invention:

1. An embossing machine, comprising a die, a counter co-operating with the die, and means for supplying a strip from a roll to said counter and die including a bushing upon which said roll is adapted to be mounted and which inclines transversely to the length of the strip.

2. An embossing machine comprising a die, a counter co-operating with the die, and means for supplying a strip from a roll to said counter and die including a bushing upon which said roll is adapted to be mounted and which inclines transversely to the length of the strip, and an inclined spindle upon which said bushing is journaled.

3. An embossing machine comprising a die, a counter co-operating with the die, and means for supplying a strip from a roll to said counter and die including a bushing upon which said roll is adapted to be mounted and which inclines transversely to the length of the strip, an inclined spindle upon which said bushing is journaled, and an inclined guide disk on which the inner end of said spindle is mounted.

4. An embossing machine comprising a die, a counter co-operating with the die, and means for supplying a strip from a roll to said counter and die including a bushing upon which said roll is adapted to be mounted and which inclines transversely to the length of the strip, an inclined spindle upon which said bushing is journaled, an inclined guide disk on which the inner end of said spindle is mounted, and a washer arranged on said spindle between the inner end of said bushing and the outer side of said disk.

5. An embossing machine comprising a die, a counter co-operating with the die, and means for supplying a strip from a roll to said counter and die including a support for the roll, a main frame, and means for adjusting said support relatively to said frame, comprising a shelf having a rear section connected with the frame, and a front section carrying said support and slidable lengthwise on said rear section.

6. An embossing machine comprising a die, a counter co-operating with the die, and means for supplying a strip from a roll to said counter and die including a support for the roll, a main frame, and means for adjusting said support relatively to said frame, comprising a shelf having a rear section connected with the frame, a front section carrying said support and slidable lengthwise on said rear section, and clips secured to one of said sections and engaging with the other section.

7. An embossing machine, comprising a die, a counter co-operating with the die, and

- means for supplying a strip from a roll to said counter and die including a support for the roll, a main frame on which said support is mounted, and a guide arranged between 5 said roll support and said die and counter, comprising upper and lower transverse rods which receive said strip between them, and guide blocks adjustably connected with said rods on opposite sides of said strip.
- 10 8. An embossing machine, comprising a die, a counter co-operating with the die, and means for supplying a strip from a roll to said counter and die including a support for the roll, a main frame on which said support 15 is mounted, and a guide arranged between said roll support and said die and counter, comprising upper and lower transverse rods which receive said strip between them, guide blocks adjustably connected with said rods 20 on opposite sides of said strip, and pivoted arms connected with opposite ends of one of said guide rods.
9. An embossing machine, comprising a die, a counter co-operating with the die, and 25 means for supplying a strip from a roll to said counter and die including a support for the roll, a main frame on which said support is mounted, and a guide arranged between said roll support and said die and counter, 30 comprising upper and lower transverse rods which receive said strip between them, and guide blocks adjustably connected with said rods on opposite sides of said strip, a shelf arranged on the front part of said frame, 35 and longitudinal supporting arms arranged on opposite sides of said strip and connected at their rear ends with opposite ends of one of said guide rods while their front ends are pivoted to said shelf.
- 40 10. An embossing machine, comprising an impressing and cutting mechanism whereby successive portions of a strip are embossed and the embossed parts are severed from the strip, and means for supporting and feeding 45 said strip past said impressing mechanism including a band which engages one side of the strip and moves with the same through the machine and which is pressed with said strip by said impressing mechanism.
- 50 11. An embossing machine, comprising an impressing and cutting mechanism whereby successive portions of a strip are embossed and the embossed parts are severed from the strip, and means for supporting and feeding 55 said strip past said impressing mechanism including an endless band which engages one side of said strip and moves with the same past said impressing mechanism and which is pressed with said strip by said impressing mechanism.
- 60 12. An embossing machine, comprising an embossing mechanism whereby successive sections of a strip are embossed and cut out of the body of the strip to form a label or seal, means for feeding said strip past said 65 embossing mechanism including a band engaging one side of said strip, and means for separating the body of the strip and the severed sections of the same.
13. An embossing machine comprising an 70 embossing mechanism whereby successive sections of a strip are embossed and cut out of the body of the strip to form a label or seal, means for feeding said strip past said embossing mechanism including an endless band 75 engaging one side of said strip in its passage past said impressing mechanism and a rod around which the rear or delivery turn of said band passes, and a separating blade arranged adjacent to the rear turn of said band and adapted to direct the perforated portion of the strip away from said band and also remove any embossed and severed sections therefrom.
14. An embossing machine, comprising an 80 embossing mechanism whereby successive sections of a strip are embossed and cut out of the body of the strip to form a label or seal, means for feeding said strip past said embossing mechanism including an endless band 85 engaging one side of said strip in its passage past said impressing mechanism and a rod around which the rear or delivery turn of said band passes, a separating blade arranged adjacent to the rear turn of said band 90 and adapted to direct the perforated portion of the strip away from said band and also remove the embossed and severed sections 95 therefrom, and means for taking up the slack in said strip adjacent to said blade.
15. An embossing machine, comprising an 100 impressing mechanism, means for moving a strip past said impressing mechanism including an endless band supporting said strip, a feed roller over which said strip and band pass, and a guide roller around which the delivery turn of said band passes independently of said strip, means arranged adjacent to said guide roller for removing therefrom any severed strip sections which may adhere 105 thereto, and means for taking up the slack in the idle part of said band adjacent to said guide roller.
16. An embossing machine comprising an 110 impression mechanism, means for moving a strip past said impression mechanism including an endless band supporting said strip, a feed roller over which said strip and band pass, and a guide roller around which the delivery turn of said band passes independently of said strip, means arranged adjacent to said guide roller for removing therefrom any severed strip sections which may adhere 115 thereto, and means for taking up the slack in the idle part of the band between said guide roller and said feed roller including a tension roller arranged below the feed roller, said feed and tension roller receiving the idle stretch of said band 120 between them.
- 125 130

17. An embossing machine comprising an impressing mechanism, means for moving a strip past said impressing mechanism including an endless band supporting said strip, a feed roller over which said strip and band pass, and a guide roller around which the delivery turn of said band passes independently of said strip, means arranged adjacent to said guide roller for removing therefrom any severed strip sections which may adhere thereto, and means for taking up the slack in the idle part of the band between said guide roller and said feed roller including a tension roller arranged below the feed roller, said feed and tension roller receiving the idle stretch of said band between them, and means for yieldingly holding said tension roller toward said feed roller.

18. An embossing machine, comprising an impressing mechanism, means for moving a strip past said impressing mechanism including an endless band supporting said strip, a feed roller over which said strip and band pass, and a guide roller around which the delivery turn of said band passes independently of said strip, means arranged adjacent to said guide roller for removing therefrom any severed strip sections which may adhere thereto, and means for taking up the slack in the idle part of the band between said guide roller and said feed roller including a tension roller arranged below the feed roller, said feed and tension roller receiving the idle stretch of said band between them, means for yieldingly moving said tension roller toward said feed roller, and means for moving said tension roller away from the feed roller.

19. An embossing machine, comprising an impression mechanism, means for moving a strip past said impression mechanism including an endless band supporting said strip, a feed roller over which said strip and band pass and a guide roller around which the delivery turn of said band passes, independently of said strip, means arranged adjacent to said guide roller for removing therefrom any severed strip sections which may adhere thereto, and means for taking up the slack in the idle part of the band between said guide roller and said feed roller including a tension roller arranged below the feed roller, said feed and tension roller receiving the idle stretch of said band between them, bearings in which said tension roller is journaled, guide rods for said bearings, springs engaging said bearings for moving said tension roller toward said feed roller, and means for moving said tension roller away from the feed roller.

20. An embossing machine, comprising an impressing mechanism, means for moving a strip past said impressing mechanism including an endless band supporting said strip, a feed roller over which said strip and

band pass and a guide roller around which the delivery turn of said band passes, independently of said strip, means arranged adjacent to said guide roller for removing therefrom any severed strip sections which may adhere thereto, and means for taking up the slack in the idle part of the band between said guide roller and said feed roller including a tension roller arranged below the feed roller, said feed and tension rollers receiving the idle stretch of said band between them, bearings in which said tension roller is journaled, guide rods for said bearings, springs engaging said bearings for moving said tension roller toward said feed roller, and means for moving said tension roller away from the feed roller, comprising cams arranged between said bearings and an adjacent abutment.

21. An embossing machine, comprising an impression mechanism, means for moving a strip past said impressing mechanism including an endless band supporting said strip, a feed roller over which said strip and band pass and a guide roller around which the delivery turn of said band passes, independently of said strip, means arranged adjacent to said guide roller for removing therefrom any severed strip sections which may adhere thereto, and means for taking up the slack in the idle part of the band between said guide roller and said feed roller including a tension roller arranged below the feed roller, said feed and tension rollers receiving the idle stretch of said band between them, bearings in which said tension roller is journaled, guide rods for said bearings, springs engaging said bearings for moving said tension roller away from said feed roller, and means for moving said tension roller toward said feed roller, comprising cams arranged between said bearings and an adjacent abutment, and a cross bar connecting said cams for operating the same in unison.

22. An embossing machine, comprising an impressing and cutting mechanism whereby successive parts of said strip are embossed and cut from the strip, an inking mechanism for inking said impressing mechanism, and means for feeding a strip to be impressed past said impressing and cutting mechanism, including an endless band which is adapted to support said strip and which is pressed with said strip by said impressing mechanism.

23. An embossing machine, comprising an impressing and cutting mechanism whereby successive parts of said strip are embossed and cut from the strip, an inking mechanism for inking said impressing mechanism, and means for feeding a strip to be impressed past said impressing and cutting mechanism, including an endless band which is adapted to support said strip and which is pressed

with said strip by said impressing mechanism, and means for intermittently advancing said strip and band.

24. An embossing machine comprising an impressing and cutting mechanism whereby successive parts of said strip are embossed and cut from the strip, an inking mechanism for inking said impressing mechanism, and means for feeding a strip to be impressed past said impressing and cutting mechanism including an endless band which is adapted to support said strip and which is pressed with said strip by said impressing mechanism and intermittently operating means for advancing said strip and band which causes said strip and band to stand still while an impression and cutting operation is produced on the strip and to move forward a step when the strip is released by the impressing and cutting mechanism.

25. An embossing machine comprising an impressing mechanism including a counter, a die movable toward and from the counter and a reciprocating cross head carrying said die, and means for inking the face of said die including a reciprocating carriage having an ink delivery roller for engaging said die, a track which is mounted on said cross head and on which said carriage is guided, a lever having a fixed fulcrum and operatively connected with said carriage, and means for transmitting motion from said cross head to said lever.

26. An embossing machine comprising an impressing mechanism including a counter, a die movable toward and from the counter and a reciprocating cross head carrying said die, and means for inking the face of said die including a reciprocating carriage having an ink delivery roller for engaging said die, a track which is mounted on said cross head and in which said carriage is guided, a main lever fulcrumed on a fixed support, linkage connecting said lever with said carriage, and means for transmitting motion from said cross head to said lever.

27. An embossing machine comprising an impressing mechanism including a counter, a die movable toward and from the counter and a reciprocating cross head carrying said die, and means for inking the face of said die including a reciprocating carriage having an ink delivery roller for engaging said die, a track which is mounted on said cross head and on which said carriage is guided, a main lever fulcrumed on a fixed support, linkage connecting said lever with said carriage, and means for transmitting motion from said cross head to said lever comprising an intermediate lever pivoted concentrically with said main lever and operatively connected with said cross head, and means for adjustably connecting said intermediate and main levers.

28. An embossing machine comprising an

impressing mechanism including a counter, a die movable toward and from the counter and a reciprocating cross head carrying said die, and means for inking the face of said die including a reciprocating carriage having an ink delivery roller for engaging said die, a track which is mounted on said cross head and on which said carriage is guided, a main lever fulcrumed on a fixed support, linkage connecting said lever with said carriage, and means for transmitting motion from said cross head to said lever comprising an intermediate lever pivoted concentrically with said main lever, a link connecting said intermediate lever with said cross head, and means for adjustably connecting said intermediate lever and main lever consisting of an adjusting rod connected with said intermediate lever and passing through said main lever, and screw nuts arranged on said rod and engaging with opposite sides of said main lever.

29. An embossing machine comprising an impressing mechanism including a counter, a die movable toward and from the counter and a reciprocating cross head carrying said die, and means for inking said die including an ink fount movable bodily with said cross head and having an ink supply roller, a rotary ink distributing plate arranged between said fount and die and movable bodily with said cross head, an inking carriage having rollers for carrying ink from said supply roller to said disk and from the latter to said die, a track which moves with said cross head and upon which said carriage is guided, and means for intermittently turning said disk by motion derived from said cross head.

30. An embossing machine comprising an impressing mechanism including a counter, a die movable toward and from the counter and a reciprocating cross head carrying said die, and means for inking said die including an ink fount movable bodily with said cross head and having an ink supply roller, a rotary ink distributing plate arranged between said fount and die and movable bodily with said cross head, an inking carriage having rollers for carrying ink from said supply roller to said disk and from the latter to said die, a track which moves with said cross head and upon which said carriage is guided, and means for intermittently turning said disk including an upright shaft journaled in a bearing mounted on the cross head and carrying said disk, a horizontal shaft journaled in a bearing mounted on the cross head and geared to said upright shaft, a ratchet wheel connected with said horizontal shaft, a ratchet arm pivoted concentrically with said ratchet wheel and having a pawl engaging therewith, a rock shaft journaled in fixed bearings and having two rock arms, and two links one of which connects

- one of said rock arms with the cross head and the other connecting the other rock arm with said ratchet arm.
31. An embossing machine comprising an impressing mechanism including a counter, a die movable toward and from the counter and a reciprocating cross head carrying said die, and means for inking said die including an ink fount movable bodily with said cross head and having an ink supply roller, a rotary ink distributing plate arranged between said fount and die and movable bodily with said cross head, an inking carriage having rollers for carrying ink from said supply roller to said disk and from the latter to said die, a track which moves with said cross head and upon which said carriage is guided, and means for intermittently turning said ink supply roller by motion derived from said cross head.
32. An embossing machine comprising an impressing mechanism including a counter, a die movable toward and from the counter and a reciprocating cross head carrying said die, and means for inking said die including an ink fount movable bodily with said cross head and having an ink supply roller, a rotary ink distributing plate arranged between said fount and die and movable bodily with said cross head, an inking carriage having rollers for carrying ink from said supply roller to said disk and from the latter to said die, a track which moves with said cross head and upon which said carriage is guided, and means for intermittently turning said ink supply roller by motion derived from said cross head, including a ratchet wheel connected with said supply roller, a ratchet arm pivoted concentrically with said ratchet wheel and having a pawl engaging therewith, a rock lever having a fixed fulcrum and operatively connected with said cross head, and a link connecting said rock lever with said ratchet arm.
33. An embossing machine comprising an impressing mechanism including a counter, a die movable toward and from said counter and a reciprocating cross head carrying said die, and means for inking said die including a guideway arranged below the cross head, means for adjusting said guideway vertically on said cross head, and a carriage slideable on said guideway and having ink rollers adapted to engage said die.
34. An embossing machine comprising an impressing mechanism including a counter, a die movable toward and from said counter and a reciprocating cross head carrying said die, and means for inking said die including a guideway arranged below the cross head, means for adjusting said guideway vertically on said cross head, including brackets which are arranged on the front side of said cross head and with which the front end of said guideway is pivotally connected, a cross piece connected with the rear end of said guideway, an adjusting bolt mounted on said cross head and passing through said cross piece, and screw nuts arranged on said bolt and engaging with opposite sides of said cross piece.
35. An embossing machine comprising an impressing mechanism including a counter, a die movable toward and from said counter and a reciprocating cross head carrying said die, and means for inking said die including a guideway arranged below the cross head, a carriage slideable in said guideway and provided with an ink roller adapted to engage with said die, and guard bars mounted on the underside of said cross head and adapted to be engaged on the underside by the opposite ends of said ink roller.
36. An embossing machine comprising an impressing mechanism including a counter, a die movable toward and from said counter and a reciprocating cross head carrying said die, and means for inking said die including a guideway arranged below the cross head, an ink fount arranged on the front end of said guideway, an ink distributing disk mounted on said guideway between said fount and cross head, a carriage slideable in said guideway and having rollers for carrying the ink from said fount to said disk and from the latter to said die, and means for regulating the discharge of ink from said fount.

GEORGE W. MIX.
